UNITED STATES PATENT OFFICE.

JOHN F. MALLINCKRODT, OF DENVER, COLORADO.

CAR-BRAKE.

SPECIFICATION forming part of Letters Patent No. 329,465, dated November 3, 1885.

Application filed November 10, 1884. Renewed September 16, 1885. Serial No. 177,305. (No model.)

To all whom it may concern:

Be it known that I, JOHN F. MALLINCKRODT, of Denver, in the county of Arapahoe and State of Colorado, have invented certain new and useful Improvements in Car-Brakes; and I do hereby declare the following to be a full, clear, and exact description of the invention, such as will enable others skilled in the art to which it appertains to make and use the same.

10 My invention relates to an improvement in car-brakes, particularly to brakes adapted to use in connection with horse-cars. Hitherto when the brake-chain has given out or tension-rods have broken street-cars, as well as 15 steam railway-cars, have met with serious damage. Especially has this been the case when the car has been running down an incline, resulting in some instances in fatally injuring passengers, and very often ruining the usefulness of the horses and damaging the cars.

The object of my present invention is to provide a system of brake mechanism in which the weight of the car will automatically put on brakes and hold them on until taken off by the 25 positive exertion of the driver, thereby reversing the ordinary system, where the exertion of the driver is employed in putting on brakes; a further object being to provide a brake system in which there shall be an equal pressure exerted upon the several wheels, thereby preventing 30 sliding and the consequent flattening of the wheels; a further object being to provide a system which shall have a neat appearance, and which shall be durable and comparatively 35 inexpensive; and with these ends in view my invention consists in certain features of construction and combinations of parts, as will be hereinafter described, and pointed out in the claims.

40 In the accompanying drawings, Figure 1 is a view of my improved system, in side elevation, applied to a car. Fig. 2 is a bottom plan view; and Figs. 3, 4, and 5 are enlarged detached views of parts.

45 A represents the bottom of a car, fulcrumed at *a* upon the opposite ends of two sets of levers, *B*. The levers *B* are preferably located beneath the outer edges of the bottom of the car and run longitudinally therewith. The 50 fulcrums *a* are located at such distances from the ends of the car that they will sustain as

nearly as possible equal portions of the entire weight. The adjacent ends of each set of levers lap each other, as shown at *b*, and are locked against spreading apart laterally by a 55 grooved roller, *C*, the edges of which lap over the laterally-opposite edges of the lapped ends of the levers. The rollers *C* are mounted on the crank-arms *d* of the shaft *D*, the latter being journaled in suitable bearings, *E*, secured 60 to the bottom of the car. The shaft *D* is squared between its bearings, and a depending arm, *F*, is provided with an oblong open slot, *f*, at one end, adapted to snugly receive the shaft *D* therein. The arm *F* is locked 65 rigidly on the shaft by a draw-bolt, *e*, which extends through the branches of the arm formed by the slot *f*, a suitable packing, *c*, being inserted between the bolt and shaft when the latter is in position in the slot. A short 70 connecting-rod, *G*, forked at each end, is pivotally secured to the lower end of arm *F* and to a live-lever, *H*, lying horizontally between the brake-beams *K* *K'*. The end of the long arm of the lever *H* is pivotally connected with 75 the central portion of the brake-beam *K'* by the rod or bar *h*, and the middle portion of the said long arm of the lever *H* is pivotally connected with the central portion of the 80 brake beam *K* by the rod or bar *k* and the lever *I*. The lever *I* is pivotally secured at one end to a depending standard, *i*, rigidly fastened to the bottom of the car, and at its opposite end to the brake-beam *K*. The rod or bar *k* is pivotally secured to the lever *I* at or near 85 its middle portion.

The object of connecting the live-lever *H* indirectly with the beam *K* is to equalize the pressure against the front and rear wheels when the brakes are applied. By noting the 90 points on the lever *H* where the rods connecting the lever with the beams *K* and *K'* are attached it will be seen that were the lever connected directly with each of the beams there would be twice as much pressure exerted upon the beam 95 *K* as upon the beam *K'*. This would be a very serious objection, as it would be apt to set the wheels acted upon by *K* while the wheels acted upon by *K'* were allowed to rotate, thereby causing the former to slide on 100 the rails and become flattened, as well as rendering the surfaces of the rails slippery and

difficult to stop on. By inserting the third-class lever I between the rod *k* and the beam K the power of *k* is reduced one-half, thereby rendering the pressure equal upon the two beams. If the bar *k* were attached nearer the end or nearer the fulcrum of the lever H, there would of course be a lesser or greater inequality between the pressures exerted upon the two beams, and to equalize the same the rod 5 *k* would be attached nearer the movable end of I, or nearer the fulcrum end, as the case might be. The short arm of lever H is connected with one end of an equal-armed lever, L, pivoted to a standard, *l*, by the rod M. The 10 opposite ends of the lever L are connected by draw-rods *m* and chains *m'* with the brake-cranks N, whereby either brake-crank operates *u*; on the short arm of lever H in drawing the brake-beams toward one another and 15 thereby taking off brakes. The car-wheels O are mounted upon suitable axles, *o*, the ends of the axles being secured in vertically-yielding boxes P, attached to the levers B. The boxes are preferably constructed as shown, 20 having a vertically-yielding motion against the tension of spiral springs *p*, secured on the guide-bolts Q, the lower ends of the bolts being held in position by a bracket brace or frame, *q*. The brakes are held off by the brake-cranks 25 at the platforms of the cars. When it is desired to stop the car, the brake-cranks are released and the weight of the car and its load is exerted on the ends of the levers B, thereby elevating the lapped ends of the said levers, 30 rotating the shaft D, and by means of arm F, connecting-rod G, live-lever H, and rods *h* and *k* pressing the brakes S, secured to the brake-beams K K', against the wheels O. This pressure will act upon the several wheels simultaneously and with equal force. A further very 35 important advantage is that the pressure will be in proportion to the load, thus requiring no more care or trouble in stopping a loaded car than an empty one, and should the draw-bar 40 or chain give way the brakes will be immediately and automatically applied, thereby enhancing the safety of the passengers and preventing injury to horses and cars.

It is evident that my system is capable of 45 numerous modifications by changing the forms and arrangement of the several parts described without departing from the spirit and scope of my invention; hence I do not wish to limit myself strictly to the construction herein set forth; but,

Having fully described my invention, what I claim as new, and desire to secure by Letters Patent, is—

1. The combination, with two sets of levers 50 fulcrumed on the axles, and a car supported on the outer ends of the levers, of a crank-shaft journaled to the bottom of the car, the cranked ends of said shaft resting in contact with the inner ends of the supporting-levers, 55 a pair of brake-beams suspended beneath the car and connected by a system of levers, and means for communicating the action of the

supporting-levers to the crank-shaft and the action of the crank-shaft to the system of levers, substantially as set forth. 70

2. The combination, with a set of levers fulcrumed on the axles, and a car supported on the outer ends of the levers, of a set of brakes suspended in a suitable position beneath the car, a system of levers connecting the brakes, 75 and mechanism connecting the inner or free ends of the supporting-levers with the system of levers connecting the brakes, whereby the weight of the car, operating through the supporting-levers, moves the brakes simultaneously in opposite directions, substantially as set forth. 80

3. The combination, with a set of levers fulcrumed on the axles, and a car supported on the outer ends of the levers, of a crank-shaft 85 journaled to the car and connected with the inner or free ends of the supporting-levers, and adapted to be rotated by the motion of the adjacent ends of the levers, and a set of brakes operated by an arm secured to the rotary shaft, 90 substantially as set forth.

4. In a brake-system, a set of levers arranged on opposite sides of the car, pivotally secured near their outer ends on the axles, and adapted to support a car on their extreme 95 outer ends and operate the brakes by the motion of their adjacent ends, substantially as set forth.

5. In a brake system, a set of levers pivotally secured on the axles, adapted to support a 100 car on their opposite ends, and having their adjacent ends locked against lateral displacement by a flanged roller on the brake-operating shaft, substantially as set forth.

6. In a car-brake, the combination, with the 105 body of the car, supporting-axles, and axle-boxes, of levers supported near their outer ends on springs secured near their outer ends to the axle-boxes, the short arms of said levers engaging the car and the longer arms connected with the brake-actuating mechanism, substantially as set forth.

7. In a car-brake, the combination, with the car-body and supporting-axles, of axle-boxes and levers supporting the car at their outer 115 ends and connected with the braking mechanism at their inner ends interposed between the axle-boxes and car-body, and supported in a yielding manner on the axle-boxes, substantially as set forth. 120

8. In a car-brake, the combination, with the car-body and supporting-axles, of brake-actuating levers, and axle-boxes suspended from or secured to said levers, substantially as set forth. 125

9. In a car-brake, the combination, with a car-body supported upon brake-actuating levers, and axle-boxes secured in vertical adjustment on guide-bolts set in the levers, of springs interposed between the boxes and 130 levers, substantially as set forth.

10. In a car-brake, the combination, with 135 brake-actuating levers fulcrumed on the axles in a yielding vertical adjustment, and a car-

body supported on the outer ends of the levers, of a crank-shaft journaled to the car and connected with the inner or free ends of said actuating-levers, and adapted to transmit the motion of the levers to the brakes, substantially as set forth.

11. In a car-brake, the combination, with a vertically-movable car-body and a set of brake-beams connected thereto, of a live-lever actuated by the movement of the car-body, and mechanism connecting the lever directly with one beam and indirectly with the other beam, whereby the pressure upon the two beams is equalized, substantially as set forth.

12. In a car-brake, the combination, with a vertically-movable car-body, brake-beams suspended therefrom, and live-lever connected with the brake-beams and actuated by the movement of the car, of draw-rods and chains connecting the live-lever with brake-cranks at each end of the car, for the purpose substantially as set forth.

13. A car-brake system consisting, essentially, of a set of levers fulcrumed on the axles, and supporting the car on their outer ends, 25 and actuated by the weight of the car, a lever connected with the brake-beams by pressure-equalizing mechanism, a crank-shaft connected with the inner or free ends of the supporting-levers for transmitting the action of the car-supporting levers to the brake-beam-actuating lever, and suitable mechanism connecting the latter with the brake-crank at the ends of the car, substantially as set forth.

In testimony whereof I have signed this 35 specification in the presence of two subscribing witnesses.

JOHN F. MALLINCKRODT.
